Specification of Letters Patent.

Patented Oct. 7, 1913.

Application filed October 8, 1912. Serial No. 724,526.

To all whom it may concern:

Be it known that I, OSCAR S. JONES, a citizen of the United States, residing at Utica, in the county of Oneida and State of New York, have invented certain new and useful Improvements in Indicators, of which the following is a specification, reference being had therein to the accompanying drawings.

10 My invention relates to an indicator and I declare the following to be a full, clear, concise, and exact description thereof sufficient to enable any one skilled in the art to which it appertains to make and use the same, reference being had to the accompanying drawings, in which like reference characters refer to like parts throughout the specification.

15 The object of the invention is to provide a simple, efficient, automatic device whereby electric street cars and other like conveyances may accurately display in a conspicuous part of the car the cross streets as the said car approaches same.

20 The device may be readily changed from one car to another and when equipped with the proper sign roll will automatically indicate the streets, as they are approached, along a given route upon both the outbound and return trips.

25 The device further anticipates the backing up of a car past any cross street or streets, so that the cross streets will be again indicated as the car backs therpast. When 30 the car again starts upon its forward direction the device will work normal. The indicator will work automatically whether the car runs upon a single track or upon a double track.

35 Furthermore, the invention may be found useful in displaying advertisements, if the owner desires to employ it in that manner.

Other objects will be observed by referring to the drawings in which:

40 Figure 1 is a front elevation of the indicator; Fig. 2 is a rear elevation of the indicator, showing the rear cover removed; Fig. 3 is an enlarged perspective view of certain wheels, ratchets and a smaller wheel for limiting the periodic movements of the curtain; Fig. 4 is an enlarged view of a star cam and immediate parts employed in the device; Fig. 5 is a detail view, somewhat enlarged of the mechanism for moving the curtain, same being shown in plan; Fig. 6 is an enlarged fragmentary view, showing a side

elevation of a ratchet and immediate parts for turning a curtain in one direction; Fig. 7 is a detail view enlarged of a U shaped member; Fig. 8 is an enlarged detail view, 60 showing a side elevation with parts in section of the means for moving the curtain; Fig. 9 is a detail enlarged view of a ratchet and immediate parts for moving the curtain in the reverse direction from that shown in 65 Fig. 6; Fig. 10 is an enlarged detail view of a hook employed to secure the mechanism shown in Fig. 5 to the frame of the machine; Fig. 11 is a side elevation of the rear door of the indicator; Fig. 12 is an enlarged 70 vertical section taken along the line indicated by 12-12 in Fig. 2; Fig. 13 is an enlarged view of a trolley and immediate parts; Fig. 14 is an enlarged front elevation of a switch box secured to the trolley 75 pole; Fig. 15 is a detail view, showing the cover for the switch box of Fig. 14; Fig. 16 is a detail enlarged view showing a bracket with plugs about to be inserted therein; Fig. 17 is a diagrammatic view of 80 the wiring of the device; Fig. 18 is a detail enlarged view of a lever employed to aid in disengaging a pawl from its adjacent ratchet.

85 Referring more particularly to the drawings, the frame work of the indicator comprises end members 1 and 2, which are secured to top and base members 3 and 4, respectively and are held at the required distance apart by sleeves as 5 and rods 6, screw 90 threaded at either end for the reception of nuts 7.

The front portion of the frame is inclosed by door 8, having an oblong opening at 9 for the displaying of the names of the 95 streets as same are passed by said opening 9 by the movement of canvas 10, which has one end secured in a suitable manner to roll 11 having flanges 12-12 and mounted in bearings at either end thereof in members 100 1 and 2. Door 8 is hinged to lower or base member 4 at 13 and is held in proper position by a screw or other locking means as 14. Curtain 10, starting with roll 11 to which one end of said curtain is secured 105 passes over roll 15, under roll 16, having at either end flanges 17-17, over the peripheries of wheels 18-18 having projections 19 which engage holes 20 in canvas or curtain 10, over roll 21 having flanges 22-22, under roll 23 to roll 24, having flanges 25-25 to which roll the opposite end of said cur-

tain 10 is secured. Rolls 11, 15, 16, 21, 23 and 24 have bearings in end members 1 and 2 of the frame. The portion of curtain 10 between wheels 18-18 is held in correct position, so as to properly face opening 9 of member 8 by a wire 26 which is secured at either end to members 1 and 2, as at 27 and 28.

The revolution of rolls 11 and 24 with respect to the rolling of curtain 10 first upon one roll and then the other is harmonized by the employment of cone pulleys 30 and 31, which are oppositely disposed with reference to each other, upon the extended portions of shafts 32 and 33, and are adapted to turn with said shafts. Rolls 11 and 24 are, furthermore, rigidly mounted upon shafts 32 and 33 to turn therewith. The maximum diameters of pulleys 30 and 31 conform with the diameters of rolls 11 or 24 plus the maximum number of turns thereon of curtain 10, and the minimum diameters of cone pulleys 30 and 31 conform with the diameter of rolls 11 or 24. The diameters between the maximum and minimum of pulleys 30 and 31 are graduated to conform with the difference in diameter of the intermediate rolling of curtain 10 on the one roll and off the other. The number of threads on pulleys 30 and 31, obviously conforms to the number of turns of curtain 10 on rolls 11 or 24. Hence the function of pulleys 30 and 31 is to compensate for the variation in diameter of rolls 11 and 24 plus the winding and unwinding of curtain 10 upon and off from rolls 11 and 24 or vice versa. Pulleys 30 and 31 are connected by cord —A— which is attached at either end to the perimeter of the respective pulleys at the location of the maximum circumferences thereof.

The means for actuating curtain 10 upon which are printed the names of the cross streets in order, whereby said names will automatically appear before opening 9 of door 8, contemplates platform 40 detachably secured to tubes 41 and 42 by hooks 43 passed through corresponding holes in said platform and secured by finger nuts 44 screw mounted upon the upper ends of said hooks 43. There are disposed upon platform 40 solenoids or magnets 45 and 46 secured in place by brackets 47 and screws 48. Magnets 45 and 46 support in a sliding manner brass bars 49 and 50, respectively. Brass being employed because same is unaffected by the electric current that passes through the magnets from time to time. Said bars 49 and 50 are connected by screw 60 threaded projections 51 with steel bars 52 and 53, respectively. Bar 52 slidingly supported in bracket 79 is pivotally connected to link 54 which is fulcrumed at 55 to arm 56 mounted to rock arm 57 and held thereto by set screw 58. Rock arm 57 has bearings

in brackets 59 and 60 and supports sector cam 61 held to said rock arm 57 by set screw 62. Sector cam 61 bears against arm 63 fulcrumed at one end to a suitable bearing 64 of bracket 59 and pivotally connected at the other end as at 65 to sector pawl 66 having tooth 67 adapted to engage the teeth 68 of ratchet 69 secured to spindle 70 by set screw 71. Pawl 66 is held normally in engagement with teeth 68 of ratchet 69 by spring 72 secured to the lower portion 73 of pawl 66 and to the under side of arm 63. End 74 of arm 63 is guided in its vertical movement by U shaped member 75. Bars 49 and 52 are connected by link 76 to bar 78. Nuts 77 being employed in making the connection. Hence any movement of bars 49 and 52 is communicated to bar 78 supported by the upper portion of brackets 79 and 80. Bar 78 has recess 81 for pivotally supporting star cam 82 held from turning in one direction by pawl 83 fulcrumed at 84 to bar 78 and held with end 85 normally in engagement with star cam 82 by spring 86 secured at 87 to pawl 82 and at 88 to bar 78.

The teeth of star cam 82 bear against pin 90 secured to bar 91 slidingly mounted in suitable bearings 92 and 93. Bar 91 is provided with tooth 94 which engages the corresponding notches 95 of wheel 96 mounted upon spindle 70 and held to turn therewith by set screw 97. Tooth 94 of bar 91 is held in normal engagement with notches 95 by spring 98 that surrounds bar 91 and abuts against bracket 92 at one end and against pin 90 or an adjacent pin in bar 91 at the opposite end. Bar 91 is further guided in its reciprocal movement by pin 99 secured to said bar and projecting through a longitudinal recess 99^a in upper horizontal portion 105 of bracket 99^b.

Brass bars 49 and 50 each have an end projecting beyond the end surface of magnets 45 and 46. Said ends are tapered as at 100-100. End 100 of bar 49 engages a pin 101 projecting from one end of lever 102 fulcrumed at 103 to bracket 104. The opposite end of lever 102 is recessed at 105 for the reception of end 106 of lever 107 fulcrumed upon bracket 108. End 109 of lever 107 supports member 110 adapted to abut, at the proper time, against pin 111 and disengage tooth 112 of sector pawl 113 from ratchet 114 secured to turn with spindle 70.

Steel bar 53 connected by screw threaded projection 51 with brass bar 50 slidingly mounted in magnet 46 is pivotally joined to link 120 fulcrumed at 121 to arm 122 rigidly mounted to rock arm 123, which supports sector cam 124, secured thereto by set screw 124^a, and has bearings in brackets 125 and 126. Sector cam 124, when rock arm 123 is turned, abuts against the under surface of arm 127 fulcrumed at 128 to the upper portion of bracket 125. The opposite

end of arm 127 is pivotally connected at 129 to sector pawl 113 and is guided in its range of movement by U-shaped member 130 secured to base 40. Spring 207 holds tooth 112 of pawl 113 in engagement with the teeth of ratchet 114.

Tapered end 100 of brass bar 50 engages the upper surface of pin 131 secured at one end to lever 132 fulcrumed at 133 to bracket 134. Lever 132 supports at its opposite end member 135 adapted to abut, at the proper time, against pin 136 secured to sector pawl 66, whereby to disengage tooth 67 of sector pawl 66 from teeth 68 of ratchet 69.

Stops 140 and 141 are located opposite the ends of brass bars 49 and 50, respectively, whereby to prevent an excessive longitudinal movement in the direction of said stops, of said bars 49 and 50. Furthermore, stops 140 and 141 may be adjusted with reference to the nearness of approach of bars 49 and 50, by set screws 142 and 143.

To operate the indicator, same is hung up by brackets 145—145 having holes 146—146, preferably in the front part of the car and plugs 147^a, 147^b, 147^c, connected to posts 148^a, 148^b, 148^c, by wires 149^a, 149^b, 149^c are inserted in metallic holes 150^a, 150^b, 150^c, in insulating bracket 160 having shoulders 161—161, whereby the interior of said bracket may be accessible. Bracket 160 is secured above the location of the indicator, by screws or other suitable means 162—162. Posts 148^a and 148^b are connected to wires 163 and 164, respectively, which wires complete a circuit with magnet 45, and posts 148^b and 148^c are joined to wires 164 and 165, which are in circuit with magnet 46. Wire 164 is common to both magnets 45 and 46. Wire 149^a leads to plug 147^a and then by wire 165^a to metal spring clip 170, secured to insulating base 171 of switch box 172, mounted on adjustable bracket 173, secured to trolley pole 174 by set screw 175. Wire 149^b leads to plug 147^b and then by wire 165^b to metal member 176, secured to insulating base 171 of switch box 172. Wire 149^c leads to plug 147^c and then by wire 165^c to metal spring clip 177 secured to insulating base 171. Member 176 has shoulders 178 for pivotally mounting at 179, lever 180 having fastened at its top end pin 181 adapted to abut against adjustable flexible spring 182 held to adjustable clamp 183 by set screw 184. Adjustable clamp 183 is secured to the guy or span wire 185^a by clamp 185 held to adjustable clamp 183 by screws 186. Bracket 173 also supports on the opposite side of the trolley wheel 187, a second switch box 188 constructed similarly to box 172 and employed when the car is making the return trip. Wires 165^a, 165^b and 165^c of box 172 are united at 190 with corresponding wires connecting the spring clips and metal member of box 188. Boxes

172 and 188 are closed by covers 191—191 having sector slots 192, whereby to permit the movement of pins 181 and 205, respectively. As the car passes a cross street, flexible spring 182 strikes either pin 181 or 205, 70 in accordance with the direction of the car, and thereby causes lever 180 to tilt or turn on its fulcrum 179, whereby the adjacent end of insulating sector member 193 secured to lever 180, will cause either one of spring 75 clips 170 or 177, in accordance with the direction of the car, to make an instantaneous contact with metal member 176. The contact will permit a current to pass through wire 165^b and down through wire 165^c, if 80 the car is moving in the direction indicated by the arrow in Fig. 14. From wire 165^c, the current passes to wire 149^c, to magnet 46 to wire 149^b to the ground. The magnetizing of magnet 46 effects a longitudinal 85 movement of steel bar 53 and brass bar 50, joined to steel bar 53 by screw threaded projection 51. The movement of steel bar 53 causes through link 120 and arm 122 a partial revolution of rock arm 123, whereby 90 sector cam 124 is actuated to elevate one end of arm 127. The elevation of the end of arm 127 causes a movement of sector pawl 113 and of ratchet 114. Immediately magnet 46 is demagnetized, bar 53 is drawn rearwardly away from magnet 46 by spring 206 and sector cam 124 is rotated to its original position to permit the elevated end of arm 127 to assume the normal position, whereupon sector pawl 113 under the influence of 100 spring 207 causes tooth 112 to slide over the next succeeding tooth of ratchet 114 and thereby engage same in preparation for the next impulse. Simultaneously with the movement of ratchet wheel 114 and spindle 105 70 to which wheels 18—18 are secured, end 100 of brass rod 50 is projected outward to depress pin 131 secured to lever 132 to thereby rotate said lever 132 upon its fulcrum and cause its end having member 135 110 to disengage tooth 67 of sector pawl 66 from ratchet 69, so that ratchet 69 will be free to turn.

When the car is on a return trip, either pin 205 of switch box 188 is engaged by a 115 flexible spring member correspondingly disposed upon span wire 185^a, whereby the current is communicated to magnet 45, or in certain instances the contact of pin 181 of lever 180 with flexible spring 182, whereby 120 to make a contact of spring clip 170 with metal member 176, will effect the same result. The contact in this instance will cause a current to pass through wire 165^a to metal clip 170 to metal member 176, to wire 165^b, to 125 wire 149^b, to magnet 45, to the ground. Magnet 45, having been charged by the current will immediately draw steel bar 52 inward toward its center, brass bar 49 being unaffected by the current. The move- 130

ment of bar 52 inward toward the center of magnet 45 causes its connection, namely link 54 to rotate arm 56 and thereby partially rock arm 57 a partial turn. The 5 rocking of arm 57 causes sector cam 61 to impinge against arm 63, whereby end 74 of arm 63 is moved downward on the arc of a circle to cause sector pawl 66 to move ratchet wheel 69 and wheels 18-18, which 10 together with ratchet 69 are secured to spindle 70. The movement of wheels 18-18 effects a movement of curtain 10. Immediately the contact of spring clip 170 is broken with metal memoer 176, spring 200 will 15 draw bars 52 and 49 back to their normal position at rest, whereupon sector cam 61 will release arm 63 from its constrained position, so that sector pawl 66, under the influence of spring 72, will cause tooth 67 of 20 sector pawl 66 to slide over the next adjacent tooth in succession of ratchet 69 and be in position to again turn said ratchet 69, when the succeeding impulse occurs.

Simultaneously with the magnetizing of 25 magnet 45, whereby to draw steel bar 52 inward, the end 100 of brass bar 49 will be projected outward against pin 101 of lever 102, so that lever 102 will be journaled upon its fulcrum 103 and the end having recess 30 105 will be elevated. The elevation of said end causes lever 107 to turn upon its fulcrum, whereby end 109 of said lever is depressed and member 110, secured to said end 109 will abut against pin 111, secured to sector pawl 113, so as to disengage tooth 112 35 of said pawl from ratchet 114 and thus permit said ratchet to turn free from any interruption.

The forward movement of bars 49 and 52 40 also effect a similar movement of bar 78, whereby star cam 82 abuts against pin 90 secured to bar 91, to thereby move bar 91 longitudinally and release tooth 94 of bar 91 from notch 95 of wheel 96. Upon the 45 release of tooth 94 of bar 91 from notch 95 of wheel 96, said wheel will be permitted to turn with spindle 70 and wheels 18-18, until the succeeding notch 95 of wheel 96 is reached, whereupon tooth 94 of bar 91 50 will be projected therein. Notches 95 are so disposed upon wheel 96, as to permit curtain 10 to move in each instance, the distance required to expose the name of the next cross street. Likewise at the time magnet 46 is magnetized to draw bar 53 inward toward its center, same will be accompanied by a like movement of bar 210 connected to bar 53 by link 211 and supported by bracket 230. Nuts 212 being employed to make the 55 connection. The movement of bar 210 will cause star cam 213, similar to star cam 82, and located in a recess in bar 210 similar to recess 81 of bar 78, to abut against pin 214 projected upward from bar 91. The abutting of star cam 213 against pin 214 will

affect a longitudinal movement of bar 91 sufficient to release tooth 94 of bar 91 from notch 95 of wheel 96, whereby wheel 96, spindle 70 and wheels 18-18 will be permitted to turn until tooth 94 reaches the 70 succeeding notch 95 of wheel 96, at which instant tooth 94 will be projected therein by the normal pressure of spring 98 heretofore described.

In Fig. 17 there is shown a diagrammatic 75 plan of the wiring of the indicator. The magnets, as will be observed in this figure are connected in multiple, with motor of of the car whereby the current employed to magnetize same will not materially interfere 80 with the running of the motor 215 of the car. The current moves, when the car is going in a given direction, from trolley wire 216 to either switch box 172 or 188 to magnets 45 or 46 to the ground. There is located between boxes 172 and 188 and bracket 162, switches 217-217, normally open, whereby the indicator may be worked manually. There is also a switch 218, which is normally closed, whereby the circuit may be 85 broken and the indicator left inoperative.

By reference to Fig. 2 it will be observed the door 8 has a wing 219 which incloses the space occupied by cone pulleys 30 and 31. The rear of the device is closed by 95 rear door 220 having hooks as 43 which engage sleeves 5 of the frame.

Having thus described my invention, what I claim as new and desire to secure by Letters Patent is:

1. In an indicator, the combination of a 100 set of wheels having projections, a curtain having signals displayed thereon, turned by said wheels, a ratchet, a sector pawl for actuating said ratchet to turn said wheels in one direction, whereby to display a given 105 set of signals, a ratchet, a pawl for actuating said ratchet to turn said wheels in the reverse direction, whereby to display said set of signals in the reverse order, and sector 110 cams for actuating said pawls.

2. In an indicator, the combination of a 115 set of wheels having projections, a curtain actuated by said wheels, signals displayed on said curtain, ratchet wheels, pawls for actuating said ratchet wheels to turn said wheels having said projections, sector cams for actuating said pawls, and electrical means for actuating said cams.

3. In an indicator, the combination of a 120 set of wheels having projections thereon, a curtain movable in opposite directions by said wheels, a ratchet, a pawl for turning said ratchet, whereby to move said wheels in one direction, a second ratchet, a pawl 125 for turning said ratchet, whereby to move said wheels in the reverse direction, sector cams for actuating said pawls, solenoids for actuating said cams, and means for limiting the degree of turn of said wheels.

4. In an indicator, the combination of a set of wheels having projections thereon, a curtain actuated by said wheels, a ratchet wheel, a pawl for actuating said ratchet wheel, whereby to turn said wheels to move said curtain in one direction, a ratchet, a pawl for actuating said ratchet to turn said wheels in the reverse direction, sector cams for actuating said pawls, solenoids for actuating said cams, a tooth and notched wheel for limiting the degree of turning of said wheels, and star cams for releasing said tooth from said notched wheel. 5
5. In an indicator, the combination of wheels having projections thereon, a curtain actuated by said wheels, a ratchet wheel, a pawl for actuating said ratchet wheel, whereby to turn said wheels in one direction, a ratchet wheel, a pawl for actuating said ratchet wheel, whereby to turn said wheels in the reverse direction, means for limiting the degree of turn of said wheels, and a star cam for releasing said means. 10
6. In an indicator, the combination of wheels having projections thereon, a curtain actuated by said wheels, ratchet wheels for turning said wheels, pawls for actuating said ratchet wheels, cams for actuating said pawls, levers for withholding one of said pawls from engagement with its adjacent ratchet wheel while the other pawl is in operation, a bar having a tapered end for actuating said levers, and means for limiting the degree of turn of said wheels having projections. 15
7. In an indicator, the combination of wheels, a curtain, actuated by said wheels, ratchet-wheels, for turning said wheels, pawls for actuating said ratchet wheels, levers for withholding one of said pawls from engagement with its adjacent ratchet wheel while the other pawl is in operation, and bars having tapered ends for actuating said levers. 20
8. In an indicator, the combination of a set of wheels having projections, a curtain actuated by said wheels, a ratchet wheel, a sector pawl for actuating said ratchet wheel, whereby to turn said wheels having projections to actuate said curtain in one direction, a ratchet, a pawl for actuating said ratchet to turn said wheels to actuate said curtain in the reverse direction, sector cams and springs for actuating said pawls, means for limiting the degree of turn of said wheels having projections, and star cam wheels for releasing said means, substantially as described. 25
9. In an indicator, the combination of a curtain having a set of signals thereon, wheels having projections for displaying said signals before an opening, pawls, ratchet wheels, engaged by said pawls, sector cams for actuating said pawls to thereby turn said wheels, means for disengaging one of said pawls, to permit one of said ratchet wheels to turn in a given direction, and means for limiting the degree of movement of said wheels. 30
10. In an indicator of the character described, the combination of a set of wheels having projections, a curtain actuated by said wheels, a ratchet wheel, a sector pawl for actuating said ratchet wheel, whereby to turn said wheels having projections to actuate said curtain in one direction, a ratchet, a pawl for actuating said ratchet to turn said wheels to actuate said curtain in the reverse direction, sector cams and springs for actuating said pawls, a notched wheel, a tooth adapted to engage said notched wheel, whereby to limit the movement of turning of said wheels having projections, and star cam wheels for releasing said tooth from said notched wheel. 35
11. In an indicator, the combination of a set of wheels having projections thereon, a curtain actuated by said wheels, a ratchet, a pawl for actuating said ratchet to turn said wheels in a given direction, a ratchet, a pawl for actuating said ratchet to turn said wheels in the reverse direction, sector cams for actuating said pawls, solenoids, brass bars, pawl releasing means, levers actuated by said brass bars, whereby to actuate said pawl releasing means, steel bars connected with said brass bars slidably mounted in said solenoids, and links and arms connecting said steel bars with said sector cams, whereby to actuate said wheels having projections. 40
12. In an indicator, the combination of a curtain having signals marked thereon, wheels having projections for moving said curtain past an opening, ratchet wheels for actuating said wheels having projections, pawls for moving said ratchet wheels, sector cams for actuating said pawls, solenoids, brass bars slidably mounted in said solenoids, pawl releasing means, levers actuated by said brass bars for actuating said pawl releasing means, steel bars connected to said brass bars, and links and arms for connecting said steel bars to said sector cams, whereby to actuate said wheels having projections. 45
13. In an indicator, a frame having an opening, a curtain, signals marked on said curtain, wheels having projections for moving said curtain past said opening, pawls for actuating said wheels, solenoids, brass bars slidably mounted in said solenoids, pawl releasing means, levers actuated by said brass bars, whereby to actuate said pawl releasing means, steel bars connected to said brass bars, means adapted to actuate said pawls and links and arms for connecting said steel bars with said means adapted to actuate said pawls, whereby said pawls will actuate said wheels having projections. 50

14. In an indicator, the combination of a curtain having signals marked thereon, wheels having projections for moving said curtain past a given location, ratchet wheels, 5 adapted to move with said wheels having projections, pawls for moving said ratchet wheels, pawl releasing means, solenoids, brass bars slidingly mounted in said solenoids, whereby to actuate said pawl releasing means, steel bars connected to said brass bars, rock shafts, and links and arms adapted to connect said steel bars to said rock shafts, whereby to actuate said pawls which 10 actuate said ratchet wheels and said wheels having projections.
15. In an indicator, the combination of a casing having an opening, a curtain having signals marked thereon, wheels for moving said curtain past said opening, ratchet wheels adapted to turn with said wheels for moving said curtain, pawls for actuating said ratchet wheels, rock arms, sector cams mounted on said rock arms and adapted to move said pawls, solenoids, brass bars mounted to slide in said solenoids, pawl releasing means, levers actuated by said brass bars, whereby to actuate said pawl releasing means, steel bars connected with said brass bars, links connecting said steel bars with 20 said rock arms, means for magnetizing said solenoids, whereby said solenoids will draw said steel bars inward to actuate said brass bars and the links connected to said rock arms, and to control the actuation of said sector cams and said pawl releasing means, and means for withdrawing said steel bars 25
- 30
- 35

from said solenoids, whereby to actuate said brass bars, said links, said rock arms, and said sector cams to their normal position. 40

16. In an indicator, the combination of a casing having an opening a curtain having signals marked thereon, wheels having projections for moving said curtain past said opening, ratchet wheels for actuating said 45 wheels having projections, pawls for moving said ratchet wheels, sector cams for actuating said pawls, brass bars, bars connected to said brass bars for actuating said cams, and said brass bars having tapered ends, means 50 engaged by the tapered ends of said brass bars, whereby to disengage said pawls from their adjacent ratchet wheels, substantially as described.

17. In an indicator, the combination, of a 55 curtain, having a set of signals thereon, wheels for displaying said signals before an opening, pawls, ratchet wheels engaged by said pawls, sector cams for actuating said pawls to thereby turn said wheels, means for 60 disengaging one of said pawls, whereby to permit one of said ratchet wheels to turn in a given direction, a notched wheel and tooth for limiting the degree of turning of said wheels, and star cams for releasing said 65 tooth from said notched wheel.

In testimony whereof I have affixed my signature in the presence of two witnesses.

OSCAR S. JONES.
